UNITED STATES PATENT OFFICE.

EDUARD SEPPELER, OF BERLIN-NEUKOLLN, AND PAUL SCHÜTTLER, OF BERLIN-HALENSEE, GERMANY.

AIR SUPPLY FOR INTERNAL-COMBUSTION ENGINES.

Application filed August 29, 1921. Serial No. 496,494.

(GRANTED UNDER THE PROVISIONS OF THE ACT OF MARCH 3, 1921, 41 STAT. L. 1313.)

To all whom it may concern:

Be it known that we, EDUARD SEPPELER and PAUL SCHÜTTLER, both citizens of Germany, residing at Berlin-Neukolln, Germany, and Berlin-Halensee, Germany, respectively, have invented certain new and useful Improvements in Air Supply for Internal-Combustion Engines (for which we have filed applications in Germany, October 13, 1919, patent granted No. 354622, and November 28, 1919, Serial No. 38,838; England, January 10, 1921, Patents Nos. 157918 and 157919; France, March 30, 1921, Patent No. 533047; Italy, April 9, 1921, Serial No. 301/1397), of which the following is a specification.

Our invention relates to devices for regulating the supply of combustion air to internal combustion engines.

20 In internal combustion engines, in which the fuel is supplied by a fuel pump, the output is regulated by altering the delivery of the pump, for instance, by increasing or reducing the pump stroke. Together with 25 the regulation of the fuel pump, the air supply must be regulated in such a manner, that per stroke or in the unit of time a greater or lesser weight of air is supplied to the engine. It is old for this purpose to 30 connect the device, by which the stroke of the pump is regulated, with a throttling disc or valve by which the supply of air is regulated, so that to every position of the fuel 35 regulating device there corresponds a definite and invariable position of the air throttling device. The ratio of fuel and air is then the same for all loads or for all pressure ratios.

Such a device can however only be used 40 so long as the number of revolutions of the motor remains substantially constant. If the number of revolutions varies considerably, it is not possible to maintain a constant ratio between fuel and air by means 45 of such a device. If the number of revolutions is increased, the fuel supply will be increased in proportion, if the adjustment of the pump is unaltered, but the supply of air would not be increased in proportion, 50 for the reduction of pressure at the throttle increases with increasing air velocity, and the weight of air drawn into the engine will be reduced accordingly.

It is an object of our invention to provide a regulating device which will always supply a correct mixture when the load or the number of revolutions is altered, so that the engine has the necessary flexibility for all conditions of operation. This is achieved by providing, besides the device 55 for adjusting the area of the air pipe, which device is connected with the fuel control, a further throttle which automatically adjusts itself according to the number of revolutions of the engine, that is the existing air 60 velocity at the throttle, so that the reduction of pressure or the weight of air drawn into the engine at each stroke is approximately 65 the same in all cases. A device capable of such self-adjustment is the so called air float, 70 that is a member of suitable form which consists of a body floating under the action of a stream of air. According to our invention we arrange an air float at the rear 75 of a throttling opening which, in a manner per se known, is adjustable as to its area in dependency upon the regulation of the fuel pump.

In the drawings affixed to this specification and forming part thereof several devices embodying our invention are illustrated diagrammatically by way of example. In the drawings

Figs. 1 to 3 show vertical sections, several modifications of the air float arrangement,

85 Fig. 4 is a similar view of another device adapted for two cycle engines.

Referring now to Figs. 1 to 3, a throttling device *a* is arranged at a suitable point of the air supply pipe, which, in a known manner, is adjusted in conjunction with the regulation of the fuel pump, for instance together with the stroke of said pump.

In the modification illustrated in Fig. 1, 90 the throttle has the form of a so-called iris diaphragm, while in Figs. 2 and 3 it is a slide. Above the throttle there is arranged an air float *b*, which may also be designed in various ways. In Figs. 1 and 2 it is so 95 designed that it is loaded only by its own weight, whereas in Fig. 3 it is closed principally by a spring *c*. In the construction illustrated in Figs. 1 and 2 the load of the float and therefore the difference of pressure produced at the throttle is constant,

whereas in the modification shown in Fig. 3 the load can be varied.

If, for example, a 100 H. P. engine is loaded with one fifth of its normal load at 5 low velocity, it will be necessary to close the throttle *a* considerably. The air supply to the engine is now heavily throttled, because the weight of the air float is distributed over a small area. If the number of revolutions increases, the composition of the mixture is not influenced, for the same quantity of fuel is supplied to the engine by the pump at every stroke as at low velocity, but the total consumption of fuel in the 15 unit of time is increased in proportion to the increase of velocity. The air supply increases in proportion, which is automatically effected by the air float *b* rising. With the air float, it is therefore possible, to supply to the motor the correct weight of air per stroke, according to the alteration of its 20 number of revolutions, without adjusting the throttle *a*, if it be adjusted to a given position. As the areas are variable, while 25 the load on the area is constant, the air velocity at the inlet opening will be constant.

If desired, it is also possible with this device, to somewhat increase or reduce the weight of air per volume of stroke, which is 30 effected by a suitable arrangement of the guiding means and loading on the float.

The arrangement shown in Fig. 3 is more suitable for this purpose. Here the flap *b* which forms the air float, is light and loaded 35 with a spring. The position of that spring and with it the direction and lever arm of the spring power can be adjusted by means of handle *d* and segment *e*. In a given position of lever *d* the load will be 40 constant for the entire stroke of the flap, whereas, if the lever *d* be displaced to either side of this position, the load will be increased or reduced with the stroke. By 45 altering the load of the spring, the amount of loading of the area can be varied in which case the slide *a* may be dispensed with.

Fig. 4 shows the application of our invention to two cycle engines. In these, the 50 air is supplied to the working cylinder *f* by means of a charging pump *g*. According to the particular embodiment of our invention, in such two cycle engines the suction or discharge valve of the charging pump is 55 replaced by the air control. The opening through which the air passes, is periodically opened and closed in this case. If the air control were simply inserted, for instance, in advance of the suction valve of 60 the charging pump, this would involve the drawback that the conditions, which have been correctly adjusted by the control, will be modified again by the valve. It is material that there should be no controlled air 65 passage behind the air regulating device.

In the embodiment illustrated by way of example in Fig. 4, the air regulator replaces the suction valve. If by means of lever *h*, which may be actuated by hand at the handle *i* or by a velocity regulator at *k*, the wedge *m* which, in a known manner, 70 adjusts the stroke of the fuel pump *l* and the slide *a* of the air control are adjusted for a given load of the engine, the flap *b* will be displaced at every stroke into a position corresponding to the existing number of revolutions, that is, it will lay open a greater or smaller sectional area according to the number of revolutions. If, however, the load is to be varied at a constant number 75 of revolutions, lever *h* is operated. On turning said lever in the direction of the arrow, the delivery of the fuel pump *l* will be reduced, and, at the same time, the area adjusted by slide *a* will also be reduced, 80 whereas the loading of the area will be increased, so that, if the flap *b* be properly designed, the correct weight of air corresponding to the weight of the fuel will be 85 supplied.

If using the air regulator instead of the air valve, the air regulator is disposed in the pipe intermediate the working cylinder *f* and pump *g*. It is not necessary that the fuel supplied by the pump should be injected into the cylinder head, but the fuel nozzles together with the air regulator may be arranged in the pipe between the working cylinder and the charging pump. 90

We claim:—

1. In an internal combustion engine in combination, a fuel pump, an air inlet, means for adjusting said air inlet in accordance with the regulation of said pump and an air-float at the rear of said air inlet. 100

2. In an internal combustion engine in combination, a fuel pump, an air inlet, a slide adjustable by hand for throttling said air inlet in accordance with the regulation of said pump and an air-float at the rear of said air inlet. 105

3. In an internal combustion engine in combination, a fuel pump, an air inlet, means for adjusting said air inlet in accordance with the regulation of said pump and a loaded flap valve at the rear of said air inlet. 110

4. In an internal combustion engine in combination, a fuel pump, an air inlet, a slide adjustable by hand for throttling said air inlet in accordance with the regulation of said pump and a loaded flap valve at the rear of said air inlet. 115

5. In an internal combustion engine in combination, a fuel pump, an air inlet, means for adjusting said air inlet in accordance with the regulation of said pump and a spring loaded flap valve at the rear of said air inlet. 120

6. In an internal combustion engine in 125

combination, a fuel pump, an air inlet, means for adjusting said air inlet in accordance with the regulation of said pump and a spring loaded flap valve at the rear of said air inlet, the spring load on said valve being arranged to remain substantially constant during the operation of said valve. 5 of said air inlet, the spring load on said valve being arranged to remain substantially constant during the operation of said valve.

7. In an internal combustion engine in combination, a fuel pump, an air inlet, 10 means for adjusting said air inlet in ac-

cordance with the regulation of said pump and a spring loaded flap valve at the rear of said air inlet, the spring load on said valve being arranged to remain substantially constant during the operation of said valve and 15 means for varying the spring load.

In testimony whereof we affix our signatures.

EDUARD SEPPELER.
PAUL SCHÜTTLER.
